[57] CLAIM

The ornamental design for a bag, as shown and described.

DESCRIPTION

FIG. 1 is a perspective view of a bag showing our new design;

FIG. 2 is a top plan view thereof;

FIG. 3 is a front elevational view thereof;

FIG. 4 is a bottom plan view thereof;

FIG. 5 is a side elevational view thereof; and,

FIG. 6 is a rear elevational view thereof.

The broken lines showing articles inside the bag are for illustrative purpose only and forms no part of the design; other broken lines represent stitch lines. The "Mega Bloks" description in broken lines on the bag is disclaimed as a part of the design.
